UNITED STATES PATENT OFFICE.

HERMAN E. ROYS, OF NEW YORK, N. Y., ASSIGNOR, BY MESNE ASSIGNMENTS, TO
UNIVERSAL INTERESTS, INC., OF NEW YORK, N. Y., A CORPORATION OF DELA-
WARE.

CIRCULATOR-HEATER.

1,388,822.

Specification of Letters Patent. Patented Aug. 23, 1921.

Application filed November 15, 1919. Serial No. 338,372.

To all whom it may concern:

Be it known that I, HERMAN E. ROYS, a citizen of the United States, and a resident of New York, in the county of New York and State of New York, have invented an Improvement in Circulator-Heaters, of which the following is a specification.

My invention relates to heaters and especially to those electric heaters designed for attachment to an air circulating device such, for example, as an electric fan of the usual type. The object of my invention is to produce a heater of this type which is of improved construction and more convenient in attachment and operation.

It is likely that this heater will be used most widely in connection with standard electric fans and for that reason I have chosen for illustration that embodiment of my heater which is particularly designed for use with these fans. In the drawings accompanying this specification and forming a part thereof:

Figure 1 represents a front elevation of my heater as applied to an electric fan with certain parts of the heater broken away to more clearly illustrate the relationship of the parts.

Fig. 2 represents a top view of the device shown in Fig. 1 showing the fan in elevation and the heater in section along the line 2-2 of Fig. 1.

Fig. 3 is a detail section of the heater along the line 3-3 of Fig. 1,

Fig. 4 is a detail illustrating the means employed for attaching the heater to the fan,

Fig. 5 is a detail showing the construction of the heating unit proper, while

Fig. 6 is a diagrammatic illustration of a fan and heater circuit which I find advantageous.

The fan which I have selected for purpose of illustration may consist generally of the base 11, motor 12, and guard 13 supported from the motor by braces 14, and provided with a front rim 15 and a plurality of generally radial rods 16 secured at their ends to an inner ring 17. This fan is provided with the usual lead wires 19 terminating in an attachment plug 18 of any desired

type and may be provided with the customary starting and controlling switch.

The embodiment of my heater selected for illustration herein may comprise a frame 55 21 formed of a single piece of sheet metal stamped into shape. This frame may comprise an inner ring 22, an outer ring 23, a raised portion 24, an inclined portion 25 connecting the rim 22 and the raised portion 24, and an inclined portion 26 connecting the ring 23 and raised portion 24. The raised portion 24 may be apertured as at 27 to permit passage of air therethrough and is preferably crowned as clearly illustrated 65 in Fig. 3 to provide for expansion of the frame upon heating. The inclined portions 25 and 26 serve to direct the air onto the heating elements.

The heating unit proper is mounted within the pocket formed by the raised portion 24 and the two inclined portions 25 and 26. This heating unit preferably comprises an inner ring 31 and an outer ring 32 provided with a plurality of aligned apertures 33 and 34 through which extend the cores 35 of the heating elements 36. Each heating element 36 may consist of a core 35 encircled just within the rings 31 and 32 by insulating washers 38 and between these washers 70 by the heating or resistance wire 39 formed as a coil surrounding the core 35 and extending between the two insulating washers 38. The various coils 39 may be connected in any suitable way, as in series, as shown. 75 The cores 35 are preferably beveled at each end as shown at 40 on an angle corresponding to the inclination of the inclined portions 25 and 26 of the frame 21 so that after the heating unit is in assembled position rotation of the heating elements is prevented by the engagement of the beveled ends 40 of the cores 35 against the inclined surfaces 25 and 26 of the frame 21. 80

I find it convenient to assemble my heating unit by first assembling the inner ring 31, then inserting the various heating elements into the apertures of this ring to project radially therefrom, then folding the incomplete outer ring about the heating elements to gradually cause it to assume the assembled position with the elements ex- 90 95 100

tending through the apertures thereof, and then securing the two ends of this outer ring in assembled position. The ends of the rings may be secured together in any suitable manner such as by means of the bolts 41.

The heating unit is preferably secured to the frame by means of a plurality of machine screws 42 passing through holes in the inclined portions 25 and 26 of the frame 10 21 and then preferably through spacers 43 to finally engage the inner and outer rings 31 and 32.

I have herein illustrated a device for securing my heater to a support, and particularly to an electric fan, which is disclosed in detail in Fig. 4. According to this arrangement the outer rim 23 of the heater is provided with a multiplicity of apertures 44 and through certain of these apertures 20 extend the rods 45 bent as disclosed in Fig. 4 to consist of hook portions 46 lying in front of and against the rim 23, loop portions 47 lying in the rear of the plate 23 and embracing the supports such as the front 25 rods 16 of a fan guard, and threaded terminals 48 extending through other apertures 44 in the plate 23 to the forward side thereof where they are engaged by suitable nuts 49 by which the terminals 48 are drawn through 30 the rim 23 to tighten the loops 47 against the supports.

In operating my heater in connection with an electric fan I find it extremely desirable to run the fan at a materially reduced speed 35 so as to receive from the fan a slow current of hot air rather than a strong blast of but slightly warm air. I also find that it is desirable to so arrange my heater that the change necessary to reduce the fan speed 40 may be made by any one having no skill in electricity. To accomplish this I prefer to provide my heater with a socket 50 of the usual type to receive the fan plug 18 and to also provide the heater with an attachment 45 cord 51 provided at its end with the plug 52 of the usual type arranged to engage in any suitable receptacle 53 connected to a source of power. I have shown the circuits resulting from this arrangement in diagram 50 in Fig. 6 wherein are illustrated the heating wire 39 connected to the plug 52 by the leads 51 and the plug 18 connected to the fan motor 12 by the leads 17. The plug 18 is shown in position in the socket 50 and the 55 socket is connected by the lead 54 to one of the leads 51 and by means of the lead 55 to an intermediate point 56 of the resistance or heating element 39. Inasmuch as the heating current is relatively large compared 60 with the fan current the current for the fan may be neglected in considering the current passing through the heating element 39 and it then becomes apparent at once that the ratio of the fan voltage to the total voltage 65 depends upon the relation of the portion of

the heater 39 ahead of the point 56 to the entire heater. In Fig. 6 I have shown the point 56 disposed substantially midway of the heating element 39 and in practice I find that this location of the point 56 provides a very desirable fan speed.

The embodiment of my heater shown in this specification is selected for purposes of illustration only and is not to be taken as a measure of my invention. There are uses 70 for my heater and advantages therein other than those which have been specifically pointed out and there are embodiments and modifications other than those herein illustrated. These uses, advantages, embodiments, and modifications are all embraced 75 in my invention, especially as they may be included in the appended claims.

I claim:

1. An electric heater for use with an electric fan comprising a heating unit and means for securing said unit to said fan, said means being constructed to coöperate with a fan of any size within a given range.

2. An electric heater for use with an electric fan comprising a heating unit and means for securing said unit to said fan guard, said means being constructed to coöperate with a fan of any size within a given range.

3. An electric heater for use with an electric fan comprising a heating unit and quick detachable means for securing said unit to said fan, said quick detachable means being constructed to coöperate with a fan of any size within a given range.

4. An electric heater for use with an electric fan comprising a heating unit and means for positively securing said unit to said fan, said means being constructed to coöperate with a fan of any size within a given range.

5. An electric heater for use with an electric fan comprising a heating unit and quick detachable means for positively securing said unit to said fan, said quick detachable means being constructed to coöperate with a fan of any size within a given range.

6. An electric heater for use with an electric fan comprising a heating unit and quick detachable means for positively securing said unit to said fan guard, said quick detachable means being constructed to coöperate with a fan of any size within a given range.

7. An electric heater for use with an electric fan comprising a heating unit and means for securing said unit to the radial members of the fan guard.

8. An electric heater for use with an electric fan comprising a heating unit and quick detachable means for securing said unit to the radial members of the fan guard.

9. An electric heater for use with an electric fan comprising a heating unit and means for positively securing said unit to the radial members of the fan guard.

10. An electric heater for use with an electric fan comprising a heating unit and means for securing said unit to the radial members of a fan guard at any point along said members. 21. In an electric heater, a heating unit comprising inner and outer rings and a plurality of heating elements supported thereby.
11. An electric heater for use with an electric fan comprising a heating unit and quick detachable means for securing said unit to the radial members of a fan guard at any point along said members. 22. In an electric heater, a heating unit comprising inner and outer rings and a plurality of radial heating elements supported thereby. 70
- 10 12. An electric heater for use with an electric fan comprising a heating unit and means for positively securing said unit to the radial members of a fan guard at any point along said members. 23. In an electric heater, a heating unit comprising apertured inner and outer rings and a plurality of heating elements each having parts projecting through an aperture in each of said rings to thus support said elements from said rings. 75
- 15 13. An electric heater for use with an electric fan comprising a heating unit and quick detachable means for positively securing said unit to the radial members of a fan guard at any point along said members. 24. In an electric heater, a heating unit comprising apertured inner and outer rings and a plurality of heating elements each having cores projecting through an aperture in each of said rings to thus support said elements from said rings. 80
- 20 14. An electric heater comprising a heating unit, a frame supporting said unit, and quick detachable means coöperating with said frame to positively secure the frame to a support. 25. A device as in claim 23, the ends of said parts being beveled to engage slant surfaces on the frame of said unit to thus prevent rotation of said elements. 85
- 25 15. An electric heater for use with an electric fan comprising a heating unit and means for securing said unit to said fan comprising a member having one end arranged to hook through an aperture in the frame of said unit, an intermediate part arranged to embrace a part of the fan, and a second end arranged to be detachably secured to said frame. 26. A device as in claim 24, the ends of said scores being beveled to engage slant surfaces on the frame of said unit to thus prevent rotation of said elements. 90
- 30 16. An electric heater for use with an electric fan comprising a heating unit and means for securing said unit to said fan comprising a U-shaped member arranged to embrace a portion of said fan and to have both ends project through apertures in the frame of said heating unit and having one end bent over to hook said member to said frame and the other end threaded to receive a nut which prevents said second end from being withdrawn from said frame. 27. In an electric heater, a heating unit comprising an inner ring, an outer ring, a plurality of heating elements extending radially between said rings, and means on said elements and said rings to prevent relative lateral motion between said elements and either of said rings. 95
- 35 17. In an electric heater, a heating unit comprising two apertured rings and a plurality of heating elements each having parts projecting through an aperture in each of said rings to thus support said elements from said rings. 28. An electric heater comprising a frame having inclined sides and a plurality of heating elements extending from side to side of said frame and having ends beveled to correspond to the inclination of said sides. 100
- 40 18. In an electric heater, a heating unit comprising two apertured rings and a plurality of elements each having a core projecting through an aperture in each of said rings to thus support said elements from said rings. 29. An electric heater comprising an annular heating unit and a deflector extending into the opening in said annulus to deflect air from said opening through said annulus. 105
- 45 19. The device as in claim 17, the ends of said parts being beveled to engage slant surfaces on the frame of said unit to thus prevent rotation of said elements. 30. An electric heater comprising a relatively flat heating unit and a plate for supporting said unit said plate having a crowned and apertured portion within which said unit is located. 110
- 50 31. An electric heater for attachment to an electric fan comprising a heating element, leads arranged to be connected to a source of power, leads arranged to supply power to said fan, and means for so connecting said leads and said heater that, while the speeds controlling switch of said fan remains effective to alter the speed of said fan, said speeds are all decreased. 115
- 55 32. An electric heater for attachment to an electric fan comprising a heating element and connections therefrom adapted to be connected to the source of power, a connection from an internal point of said element adapted to be connected to said fan, and a second connection from said source of power to said fan. 120
- 60 65 20. The device as in claim 18, the ends of said cores being beveled to engage slant surfaces on the frame of said unit to thus prevent rotation of said elements. 13. 130

33. An electric heater for attachment to an electric fan comprising a plug arranged to connect said heater to a source of power, a receptacle on said heater arranged to receive the plug on said fan, and connections between said receptacle and said heater circuit.

34. An electric heater for attachment to an electric fan comprising a plug arranged to connect said heater to a source of power, a receptacle on said heater arranged to receive the plug on said fan, and connections between said receptacle and said heater circuit so arranged as to reduce the speed of said fan.

35. An electric heater for attachment to an electric fan comprising a plug arranged to connect said heater to a source of power, a receptacle on said heater arranged to receive the plug on said fan, and connections between said receptacle and said heater circuit so arranged that, while operation of

the speed control switch on said fan is still effective to vary the fan's speed, the fan speeds are all reduced.

36. An electric heater for attachment to an electric fan comprising a plug arranged to connect said heater to a source of power, a receptacle on said heater arranged to receive the plug on said fan, and connections between said receptacle and said heater circuit arranged to shunt said fan around part of said heater.

37. An electric heater for attachment to an electric fan comprising a plug arranged to connect said heater to a source of power, a receptacle attached to said heater arranged to receive the plug on said fan, and connections between said receptacle and said heater circuit.

In testimony whereof, I have signed my name to this specification this 13th day of November, 1919.

HERMAN E. ROYS.
